CLAIM

The ornamental design for a coin-sorting and counting machine, as shown and described.

DESCRIPTION

FIG. 1 is an isometric frontal view of a coin-sorting and counting machine showing my new design;

FIG. 2 is a front elevational view thereof;

FIG. 3 is a top plan view thereof; and

FIG. 4 is a left side elevational view thereof, the right side elevational view being a mirror image thereof.

The rear of the coin-sorting and counting machine is plane and unornamented.
